UNITED STATES PATENT OFFICE.

DAVID ROTH, OF CLEVELAND, OHIO, ASSIGNOR TO ARNSTEIN BROS. & MIER, OF SAME PLACE.

DESIGN FOR A CAMPAIGN-BADGE.

SPECIFICATION forming part of Design No. 24,953, dated December 10, 1895.

Application filed October 23, 1895. Serial No. 566,665. Term of patent 3½ years.

To all whom it may concern:

Be it known that I, DAVID ROTH, a citizen of the United States, residing at Cleveland, in the county of Cuyahoga and State of Ohio, have invented and produced a new and Original Design for a Campaign-Badge, of which the following is a specification, reference being had to the accompanying drawing, showing a part thereof.

5 The figure is a front elevation of my newly invented badge.

The leading features of my design consist in two men, one sitting in a chair and the other lying under the chair, both supported on a bar, and a pin attached to the bar for 15 attaching the badge to a garment.

A represents a man seated in an arm-chair B, and C represents a man lying under the said chair. The chair and prostrate figure are represented supported on a bar D, and 20 E is a pin for attaching the badge.

What I claim is—

The design for a campaign badge herein shown and described.

DAVID ROTH.
